WILLIAM C. TREGONING, OF CLEVELAND, OHIO.

SNAP-SWITCH FOR ELECTRIC USES.

1,207,097.

Specification of Letters Patent.

Patented Dec. 5, 1916.

Application filed October 28, 1914. Serial No. 868,613.

To all whom it may concern:

Be it known that I, WILLIAM C. TREGONING, a citizen of the United States, residing at Cleveland, in the county of Cuyahoga and State of Ohio, have invented certain new and useful Improvements in Snap-Switches for Electric Uses, of which the following is a specification.

This invention relates to a snap switch for electric uses, and the invention consists of a switch having a spring pressed actuating member and constructed and adapted to operate substantially as shown and described and particularly pointed out in the claims.

In the accompanying drawings, Figure 1 is a side elevation of the complete switch, and Fig. 2 is a sectional elevation thereof centrally through the switch member. Fig. 3 is a cross section on a line corresponding substantially to 3—3, Fig. 2. Fig. 4 is a cross section corresponding substantially to line 4—4, Fig. 2. Fig. 5 is a cross section corresponding substantially to Fig. 4 but with the push member thrust in the opposite direction. Fig. 6 is a sectional elevation on line 6—6, Fig. 3. Fig. 7 is a sectional elevation on line 7—7, Fig. 4. Fig. 8 is a perspective detail of one of the two contact plates. Fig. 9 is a perspective view of the band, or sleeve, which serves as a spring holder and switch member. Fig. 10 is a perspective view of the operating or push member. Fig. 11 is a detail of the spring. Fig. 12 is a sectional view of a modification.

As thus shown, the complete device comprises sundry essential parts consisting of a body, having two portions or halves *a* and *a'*, respectively, an actuating or operating member *m* adapted to be pulled, pushed or thrust lengthwise, a spring *s* operatively associated with said member and a spring holder or band *b*, and contact or terminal plates or parts *c*. The said body *a*—*a'* is sectional and consists of porcelain or other non-conducting material and in the present showing the sections or halves thereof run in what may be termed a lengthwise direction of the said body and are constructed on their inner or meeting faces or portions with recesses of different depth to accommodate the other parts above enumerated. Thus, the said terminals or contacts *c* are fixed oppositely in recesses in the body section *a'* and provided with binding screws

2, and the push or actuating member *m* extends transversely through both the sections *a* and *a'* and has an enlarged middle portion 3 which is transversely recessed and has the spring *s* lying therein with its ends engaged over the lugs 4 on the inside of the metal band *b*. This makes the band *b* the confining member for the spring, while the part *m* coats therewith and is the operating or actuating member in one form of the device. Push or pull in one direction establishes contact between the said terminals *c* and the band *b* to close the electric circuit, see Fig. 4, and the push in the opposite direction disengages said parts and opens the switch, see Fig. 5. The spring *s* is the reversing or throwing part for the band *b*. Thus, in the thrust movement of the bar *m*, the spring is compressed in the first half of the movement until the spring is absolutely straight longitudinally and as it passes the dead center, it immediately comes into action and finishes the movement with a quick or snapping action. That is, the band *b* is forced quickly in a reverse direction. At first, the thrust movement of the part *m* is manual, then the spring completes the movement and shifts the band in a reverse direction. Then the parts are held by the spring in the changed position until member *m* is again moved initially by hand. The member *m* is made in one piece but it might be made in separate pieces and is preferably all or in part of nonconducting material.

Obviously, the shape or style of the body *a*—*a'* may be considerably modified without changing the character thereof, but the sectional feature is preferably though not necessarily retained. As shown herein a screw shell 5 serves to bind the sections *a*—*a'* separably together.

The current conducting wires 6 are shown as connected in Fig. 7 to the binding screws 2, and the contact plates *c* are fixed by any suitable means in the sides of the body section *a'*. The transverse opening through the actuating member *m* and the length of throw of the said member are within such limits that the ends of the spring never leave the lugs 4 though they bear against opposite sides thereof in the two opposite positions which the spring assumes in action, Figs. 4 and 5, for example. It will also be noticed that the spring *s* is held by its confined relation to the parts *b* and *m* rather

than being secured to either. The part *m* also has a predetermined limit of play within body *a*—*a'* so that co-operative movement may be obtained. The spring shown herein is a straight coil of wire when not in working engagement with the parts, and the band *b* is rectangular and loosely fitted over the flat-faced, enlarged portion 3 of the thrust or operating member *m*. Twisting or turning of the band is prevented by the flat bearing relations between it and member *m*, and said member is also prevented from turning by the flat sides of its reduced ends. This makes a very simple combination of parts which will not wear out, bind or become loose or detached, and the operating space occupied by said parts is reduced to the minimum. As shown herein the sides of the body 3 of the push member or bar *m* are recessed lengthwise at 8 to confine and back the spring at its ends, thereby preventing the ends of the spring from springing or working out of place and the open ends of the spring have fulcrum relations with 25 the lugs 4.

In Fig. 12, I show a modified form of the invention in which the sleeve or band *b'* is adapted to become the actuating member. A finger hold 9 sliding in a slot 10 in the 30 casing or receptacle 11 serves as the means for shifting the band to one side or the other, and the member *m'* having the spring *s'* becomes the part adapted to reciprocate with a snap movement. Electrical contact is established by the part or parts *c'*.

The parts *b*, *m* and *s* may be embodied in a pendant switch body, or in a wall switch body, and they may also be utilized in other ways and in other devices where a quick 40 snap action is desired.

What I claim is:

1. An electric switch comprising a body and electric terminals supported thereby, an actuating member slideable within fixed 45 limits in said body and having an enlarged middle portion, a band sleeved over the said middle portion and a spring compressible longitudinally of its axis extending through the said band into engaging relations with 50 said device at its ends and opposite stops on said body for said band.

2. A switch as described, comprising a sectional body and a pair of terminals in one of said sections, an actuating bar there-

in having a transverse opening, a rectangular contact device slidably mounted upon said bar and a spring through said opening having fulcrum engaging relations at its ends with the ends of said device and adapted to throw the same into and out of contact 65 position on said terminals.

3. An electric switch comprising a sectional body provided with an internal recess, electric terminals oppositely in said recess, an actuating member having a transverse opening at its middle, a band sleeved over said member having lugs and a spiral spring extending through said opening into engaging relations with said lugs at its ends and adapted to shift said band into and out 70 of contact with said terminals.

4. In a switch, a body, a reciprocable bar having a transverse opening and an enlargement at its middle provided with channeled sides, a box-shaped member mounted over 75 said enlargement and a coil spring extending through said opening in the bar and engaged at its ends with said member and confined within said channeled sides.

5. In a switch, a body and an actuating 80 part slideable therein and having a transverse opening at its middle and channeled sides oppositely at said opening, in combination with a band about said actuating part and a coiled spring loosely mounted within said opening and loosely engaged at its ends in fulcrum relations with said band.

6. In a switch, a reciprocable member having a transverse passage and longitudinal channels at opposite sides open to said passage, in combination with an actuating spring through said opening and adapted to lie in said channels at its end portions and hold its working relations. 90

7. In a switch, a reciprocable member having flat faces and a transverse opening, in combination with a flat sided band in sleeved relations with said member and provided with lugs at its ends, and a coiled spring mounted in said opening and engaged at its 100 ends with said lugs.

In testimony whereof I affix my signature in presence of two witnesses.

WILLIAM C. TREGONING.
